DESIGN FOR A TABLE

Rudy Bruner, New York, N. Y.

Application February 2, 1944, Serial No. 112,418

Term of patent 14 years

(Cl. D33—14)

To all whom it may concern:

Be it known that I, Rudy Bruner, a citizen of the United States, residing in New York, in the county and State of New York, have invented a new, original, and ornamental Design for Tables, of which the following is a specification, reference being had to the accompanying drawing, forming a part thereof.

The figure is a perspective view of a table, showing my new design.

I claim:

The ornamental design for a table, as shown.

RUDY BRUNER.
